STADIA ROD

Robert E. McMackin and Henry P. Becker, Dallas,
Tex.; said Becker assignor to said McMackin

Application January 14, 1946, Serial No. 641,107

1 Claim. (Cl. 287—99)

1

This invention relates to surveyor's equipment and it has particular reference to certain new and useful improvements in stadia rods.

The principal object of the invention is to provide a stadia rod for surveyors which is constructed in hinged sections foldable one upon the other, rendering the same more convenient to transport from place to place and further, to produce the rod sections from extruded stock characteristically light in weight yet durable and of lasting quality.

Another object of the invention is to provide a stadia rod in hinged sections, in which the sections, when elongated or disposed in end to end relationship are secured in such position by a spring loaded latch, automatic in its closing operation but readily released by the simple expedient of depressing a lever in close proximity to one of the rod sections. Moreover, the construction provides correlated lugs at the extremities of the sections which, upon the folding of the sections engage one with the other to hold the sections in parallelism to obviate strain on the hinge.

With the foregoing objects as paramount, the invention has further reference to certain features of accomplishment which will become apparent as the description proceeds, taken in connection with the accompanying drawing wherein:

Figure 1 is a perspective view of a stadia rod constructed according to the invention in a vertical plane, showing the sections extended but broken away at intermediate points.

Figure 2 is a fragmentary view, showing the sections folded and in longitudinal section.

Figure 3 is a detail view of one of the sections in transverse cross-section.

Figure 4 is a fragmentary perspective view in vertical section of one end of one of the stadia rod sections showing one of the spacing lugs, and

Figure 5 is an elevational view of Figure 4, rotated 90°, shown in vertical section.

Continuing with a more detailed description of the drawing, reference numeral 10 denotes complementary rod sections which are extruded from light material, such as aluminum or a suitable plastic to produce an elongated body of triangular form in transverse section. To lend strength to the sections, a longitudinal web 11 is formed within the sections, dividing the interior into equi-lateral triangular voids.

The sections 10 are joined together at one end by means of a hinge 12 and the juxtapositioned ends of the sections are closed by means of plugs

13, to accommodate which, the webs 11 are terminated short of the ends of the sections to define a recess. The plugs 13 are provided with flanges 14 which are flush with bifurcated ears 15, formed with angular flanges 16, conforming to the angles of the triangular sections 10 to which they are affixed by riveting, welding or otherwise. When the sections 10 are extended or disposed in axial alignment in the manner shown in Figure 1, the ears 15 fall into alignment and the slots therein become flush.

Within the slot of one of the ears 15 is pivoted at a lever 17, to which is attached a handle 18 having a ball grip 19. Underlying the lever 17 is a coiled spring 20 which resists movement of the handle 18 towards the rod section to which it is attached. The opposite end of the lever 17 extends beyond the end of the rod section and a substantially semi-circular slot or recess 21 is made therein. Complementary to this recess is a pin 22 extending transversely across the slot of the ear 15 affixed to the companion rod section 10 and, upon bringing the sections 10 into axial alignment, as shown in Figure 1, the cam surfaced end b of the lever 17 bears against the pin 22, elevating the end of the lever in order that the pin 22 may be received in the recess 21 in the lever to prevent relative movement of the sections 10 in either direction and to hold the sections in positive alignment. Thus, the rod sections are firmly held in extended or operative relationship. To release the sections so that they may be again folded, it is simply necessary to depress the handle 18 to elevate the lever 17.

When in folded position, it is desired that the sections be disposed in strict parallelism, to obviate strain on the hinge 12. To accomplish this a plug 23 is inserted into the free end of each of the sections 10 and these plugs are each held in place by pins or bolts 24. Each plug 23 has a flanged end 25, one of which is recessed at 26 (Fig. 4) while the flange of the opposite plug is provided with a protuberance 27 which is conformably received in the said recess 26 to maintain relative spacing of the free ends of the sections equal to that at the hinged ends thereof, thus avoiding strain on the hinge 12.

It is pointed out that by producing the rod sections by extrusion the most difficult rolling operation necessary to join the edges of a sheet of metal in tubular form is obviated. While the sections may be so produced, although at greater expense than the extrusion method, such a construction would be impractical for a stadia rod due to the abuse to which they are sometimes

subjected, resulting frequently in irreparable damage because of the lack of adequate reinforcement.

The hollow extruded rod sections 10 are protected against entry of foreign matter by the plugs 13 and 23 at each end and while the rod as a whole may be slightly greater in weight than a rod constructed of wood, the latter lacks the durability of the rod of extruded sections and hence must be repaired or replaced more frequently.

Manifestly, the construction as shown and described is capable of some modification and such modification as may be construed to fall within the scope and meaning of the appended claim is also considered to be within the spirit and intent of the invention.

What is claimed is:

A stadia rod comprising sections connected together by a hinge at one end for foldability, one upon the other and held apart at their connected ends by the hinge, a pair of ears at the side opposite the hinge and attached exteriorly to each of said sections adjacent their hinged ends, a keeper in one of said pairs of ears; a lever actu-

ated latch pivotally retained in the other of said pairs of ears and having a semi-circular slot therein adapted to be engaged with opposite sides of the keeper when said sections are in axial alignment, a spring normally urging said latch toward engaged position, said sections being hollow; and plugs closing the adjacent ends of the sections.
